ELECTRICALLY CONTROLLED HYDRAULIC PRESS

Paul E. Flowers, Mount Gilead, Ohio, assignor to
 The Hydraulic Development Corporation, Inc.,
 Wilmington, Del., a corporation of Delaware

Application August 31, 1939, Serial No. 292,934

12 Claims. (CL 60—52)

This invention relates to presses, and in particular, to electrically-controlled hydraulic presses.

One object of this invention is to provide an electrically-controlled hydraulic press with its electrical and hydraulic units assembled in compact housings so as to conceal them and protect them from dust and other damaging influences.

Another object is to provide an electrically-controlled hydraulic press having its electrical and hydraulic units mounted in inclosed housings in the head and bed of the press, respectively, and arranged in compact yet easily accessible assemblies.

Another object is to provide a hydraulic press with a head member and a bed member, one of these members having the principal hydraulic units mounted theron and inclosed by a housing, and the other member having the principal electrical units similarly mounted and inclosed.

Another object is to provide a hydraulic press having a pump and a flow-control member actuated by a press control rod, which in turn, is under the control of a solenoid mounted in the bed of the press.

Another object is to provide a hydraulic press control system, as set forth in the preceding paragraph, wherein the solenoid is under the control of one or more limit switches, means being provided to restrict the effective action of the switch to one direction only of actuation.

Another object is to provide a hydraulic press control system including an electrical circuit for selectively effecting semi-automatic and full automatic operation of the press ram under the control of a limit switch, which is effective only to change the energization of the circuit by actuation in one direction and not in the opposite direction.

Another object is to provide a hydraulic press control system having an electrical control circuit for selectively effecting semi-automatic and full automatic operation of the press, together with a pair of limit switches so arranged as to alter the energization of the electrical circuit by actuation in one direction but not in the opposite direction.

In the drawings:

Figure 1 is a perspective view of a commercial form of press embodying the control system of the present invention.

Figure 2 is a diagrammatic view, mainly in section, showing the hydraulic circuit for operating the press shown in Figure 1.

Figure 3 is a side elevation of the press shown 55

in Figure 1, with the housings removed or cut away to disclose the operating mechanism therebeneath.

Figure 4 is an enlarged view of a portion of Figure 3, showing the press control rod and the associated limit switches in a position wherein the press-operating solenoid is energized for producing a forward stroke of the press.

Figure 5 is a view similar to Figure 4, but with the solenoid deenergized and the press control rod pushed down for effecting a return stroke of the press ram.

Figure 6 is a wiring diagram of the electrical control circuit employed in the press of Figures 1 to 5, inclusive.

Figure 7 is an enlarged front elevation, partly in section, of the bed of a press and a modified control system whereby a single limit switch is actuated in but one direction of travel of the press control rod.

Figure 8 is a bottom plan view of the switch-actuating mechanism of Figure 7.

Figure 9 is a side elevation, partly in section, of the switch-actuating mechanism of Figure 7, showing the limit switch being actuated on the up-stroke of the press control rod.

Figure 10 is a view similar to Figure 9, but showing the limit switch being avoided by the switch-actuating mechanism on the down-stroke of the control rod.

Figure 11 is a side elevation, partly in section, showing the hand control lever and its associated mechanism for actuating the press control rod by hand.

Figure 12 is a diagram of the electrical circuit associated with the press of Figures 7 to 11, inclusive.

General arrangement

In general, the hydraulic press control system of this invention is associated with a press having a reversible hydraulic motor, a source of pressure fluid and a flow-control member, whereby the pressure fluid is reversibly distributed to the motor. The control rod of the press which shifts the flow-control member associated with the source of pressure fluid, such as a pump, is actuated by a solenoid placed in the base of the press. Associated with the solenoid is a limit switch system which is rendered effective to energize the solenoid in but one direction of motion of the control rod. In one embodiment of the invention (Figures 1 to 6) this uni-directional actuation is effected by the use of a pair of limit switches, whereas in the modification (Figures

7 to 12) this is effected by mechanical means engaging a single limit switch.

Hitherto, it has been difficult to completely inclose the operating parts of a hydraulic press, particularly as regards the electrical and hydraulic accessories. Nevertheless, it is frequently found advisable to do this because of the presence of dust or other damaging substances, which injure these accessories. It has also been found advisable in recent times to inclose these accessories within housings in order to present a more compact appearance and also to prevent the accidental damage of these accessories by contact with external objects. At the same time the operator is protected from injury by the presence of these housings.

Hitherto, the flow-control member of the reversible variable delivery pump (in a closed circuit) or the valve member of the main control valve (in an open circuit) has been shifted in at least one direction by an electrical solenoid, shifting in the opposite direction having been usually accomplished by means of a spring. Previously the solenoid was mounted in a position adjacent the pump, or valve, but this position was remote from the switches, magnetic contactor and other electrical units additionally associated with the control circuit. This was particularly true where the pump and other hydraulic units were mounted upon the press head out of reach of the operator.

The present invention enables the solenoid to be mounted in the bed of the press adjacent the other electrical apparatus of the control circuit. Means, however, is provided for controlling the solenoid so that it is energized in but one direction of motion of the control rod. In one form of the invention (Figures 1 to 6) the solenoid is under the control of a main limit switch and an auxiliary limit switch, the latter merely conditioning the circuits of the main limit switch for operation. These two limit switches are operated by a cam upon the press control rod so that full automatic operation of the press is brought about when the platen reaches the end of its retraction stroke and raises the control rod so as to actuate the limit switches and reenergize the solenoid. In the modified form of the invention (Figures 7 to 12) a single main limit switch is employed for effecting full automatic operation and reenergization of the solenoid at the end of the return stroke of the platen, actuation of this limit switch in one direction only being insured by a special mechanical arrangement associated with the press control rod. Either of these forms of the invention enables the solenoid to be concealed within the base of the press adjacent the other electrical apparatus so that short wiring is permitted and a more compact distribution of the electrical units obtained.

External construction of press

Referring to the drawings in detail, Figure 1 shows a perspective view of a press embodying either of the control systems of this invention. This press consists of a bed 10 connected by strain rods 11 to a head 12. The bed 10 is inclosed by a housing 13 having a closure or door 14 in the lower part thereof. The space within the housing 13 is utilized as a compartment for the electrical apparatus associated with the electrical control system. The bed 10 and head 12 are also interconnected by side members 15 serving to partially inclose the strain rods 11 and also the push-back cylinders 16, having push-

back plungers 17 connected at their upper ends to the press platen 18. The latter is connected to the main plunger 19, reciprocable in the main cylinder 20, only the lower end of the latter being visible. Mounted upon the press head 12 is a fluid container or surge tank 21 having a gauge 22 for indicating the level of the oil or other working liquid therein. The press head 12 is provided with a shelf 23 upon which a housing 24 is supported. The housing 24 serves to receive and inclose certain of the hydraulic apparatus for the press, such as the pump and driving motor. A hand lever 25, mounted upon a shaft 26 supported in the press bed 10, serves for the manual control of the press when the electrical control system is not in operation.

Hydraulic circuit of press

The hydraulic circuit for actuating the press is shown diagrammatically in Figure 2. The platen 18 is connected on its upper side to the main plunger 19 reciprocating in the main cylinder 20, and is connected on its lower side to the push-back plungers 17 reciprocating in the push-back cylinders 16. Pressure fluid for operating these cylinders and advancing and retracting the respective plungers is provided by the pump 27, which may be of any suitable type. The pump 27 withdraws fluid through the suction line 28, and discharges pressure fluid through the line 29 leading by way of the check valve 30 to the main four-way control valve 31. A branch line 32 also leads from the line 29, by way of the pressure relief valve 33 and check valve 34, to the interior of the surge tank 21, and serves to discharge pressure fluid when the pressure delivered by the pump 27 exceeds the setting of the pressure relief valve 33.

The four-way valve 31 is provided with a valve rod 35 connected to the press control rod 36, which carries a collar 37 adapted to be engaged by the platen arm 38 extending laterally from the platen 18. The control rod 36 also carries a cam 39 adapted to engage and actuate the contact portions 40 and 41 of the automatic restarting switch 42 and the circuit-conditioning switch 43. The control rod 36 terminates at its lower end in a connection 44 joining it to one end of a lever 45, which is pivotally mounted as at 46 to a bracket 47 mounted on the press frame, and having a pivotal connection 48 with the armature 49 of a "push" type solenoid 50. The construction shown diagrammatically in Figure 2 is illustrated more in detail in Figure 3.

The four-way main control valve 31 is provided with discharge conduits 51 and 52, and an exhaust conduit 53 with a check valve 54. The exhaust conduit 53 leads to the interior of the surge tank 21, whereas the discharge conduit 51 leads to the upper end of the main cylinder 20. The discharge conduit 52, on the other hand, leads to the lower ends of the push-back cylinders 16, and has a branch conduit 55 leading to the operating chamber 56 of the surge valve 57 mounted in the upper end of the main cylinder 20. A pressure-responsive switch or tonnage control 58 is connected by the conduit 59 to the upper end of the main cylinder 20 and by the exhaust conduit 60 to the interior of the surge tank 21.

Electrical control circuit of press

The electrical control circuit for controlling the various movements of the press (Figure 6) includes a motor 61 operatively connected to the

pump 27 and energized by the lines 62, 63 and 64 from the branch power lines 65, 66 and 67, by way of the switch blades 68, 69 and 70 attached, with the switch blade 71, to the armature 72 of the motor contactor 73 having an operating coil 14, one end of which is connected by the line 75 to the branch power line 65. The branch power lines 65, 66 and 67 are connected, respectively, to the main power lines 76, 77 and 78. The switch blade 71 of the contactor 73 serves as an interlock for providing sustained energization of the motor contactor operating coil 14 when the momentary motor starting switch or push-button switch 79 is released after being depressed by the operator. For this purpose the line 80 runs from one pole of the switch blade 71 to one pole of the motor starting push-button switch 79, and thence to one pole of the motor stopping push-button switch 81.

The starting push-button switch 79 is normally open and the stopping push-button switch 81 normally closed. The remaining pole of the latter is connected by the line 82 to the remaining end of the motor contactor operating coil 14. The remaining pole of the motor starting push-button switch 79 is connected by the line 83 to the remaining pole of the switch blade 71, and thence to the branch power line 66. As a consequence, when the motor push-button starting switch 79 is momentarily depressed by the operator, the consequent energization of the operating coil 14 closes the magnetic contactor 73 and energizes the motor 61. This starts the pump in operation and supplies pressure fluid to the press circuit. At the same time, the switch blade 71 interconnects the lines 83 and 80 to bridge the contacts of the motor starting push-button switch 79 so that the energization of the operating coil 14 is maintained even when the push-button switch 79 is released by the operator. If it is desired to stop the motor the operator merely depresses the normally closed push-button stopping switch 81.

The press control circuit is energized from the branch power lines 84 and 85, and includes a main magnetic contactor 86, the solenoid 50, an auxiliary magnetic contactor 87, the combined momentary contact and selector switches 88 and 89 and a forward push-button switch 90. The circuit also includes the limit switches 42 and 43, previously mentioned, for controlling the full automatic operation of the press, together with the pressure-responsive tonnage control limit switch 58. Also provided is an oil temperature limit switch 91, which is controlled by a thermostat to open when the temperature of the oil, or other working fluid, exceeds the setting of the thermostat. In such event the opening of the switches terminates the automatic operation of the press. A position-responsive limit switch 92, operated by the platen, is also provided as an additional safety feature for preventing overrun of the platen. The combined momentary contact and selector switches 88 and 89 in their details and of themselves are described in the copending application of Walter Ernst, Ser. No. 292,931, filed August 31, 1939.

The switch 88 normally rests in the solid-line position designated "Forward," but it may be moved into the "Semi-automatic" position or "Full automatic" position and locked in these positions at the will of the operator. Thus the switch 88 serves not only as a push-button switch but also as a selector switch for selecting either semi-automatic or full automatic operation.

5 Semi-automatic operation occurs when the press platen makes a forward stroke, reverses, makes a retraction stroke and then comes to a halt. Full automatic operation, on the other hand, occurs when the press platen makes a forward stroke, reverses, executes a retraction stroke and halts only momentarily before beginning another forward stroke, thereby repeating an indefinite number of working cycles until halted by the operator, or by one of the safety switches. The switch 89 is normally engaged in a position designated "Automatic," but it may be shifted into the reverse position indicated by the dotted lines in Figure 6. The position marked "Hand" is merely for the purpose of deenergizing the entire control circuit so that the press is controlled by the shifting of the hand lever 25.

20 The combined switch 88 is connected by the line 93 to one pole of the forward push-button switch 90, the opposite pole of which is connected by the lines 94 and 95 to one pole of the automatic restarting switch 42 and to the branch power line 84, respectively. From the opposite pole of the automatic restarting switch 42 the line 96 runs to 25 one pole of the auxiliary contactor 87. The latter is provided with switch blades 97 and 98, upon an armature 99 actuated by the operating coil 100. From the opposite pole of the switch blade 97 the line 101 runs to one of the full automatic 30 contacts of the combined switch 88, from the remaining contact of which the line 102 runs to one of the interlock contacts of the main contactor 86. The auxiliary contactor 87 is energized by the line 103 connected to the branch power line 84, and its opposite end is connected to the line 104 running to one pole of the circuit-conditioning switch 43, the other pole of which is connected to the line 105. The closing of the contactor 87 thus closes the circuit between the 35 lines 96 and 101, through the switch blade 97, and between the lines 104 and 105 by way of the interlock switch blade 98.

40 Beyond the circuit-conditioning switch 43 the line 106 runs to a junction with the line 107 leading from one of the automatic poles of the combined switch 89 to one end of the operating coil 108 of the main magnetic contactor 86, the opposite end of which is connected by the line 109 to the same pole to which the line 102 is connected, namely, an interlock pole engageable by the interlock switch blade 110. The opposite 45 pole of the latter is connected by the line 111 to the branch power line 84, and by the line 112 to an automatic pole of the combined switch 89 by way of the resistance 113 and pilot light 114. The main magnetic contactor 86 is also provided with switch blades 115 and 116 mounted on the same armature 117 upon which the interlock blade 110 is mounted, and operable to connect and disconnect the solenoid 50 from the branch power lines 84 and 85.

Operation

50 In the operation of the press shown in Figures 1 to 6, inclusive, the operator momentarily depresses the motor starting switch 79, thereby energizing the motor 61 by way of the contactor 73. The previously described holding circuit through the interlock switch blade 71 maintains the energization of the motor 61 when the push-button switch 79 is released. The operation of the motor 61 causes the pump 27 to deliver pressure fluid. For semi-automatic operation the operator then simultaneously depresses the switches 88 and 90 with his two hands, thus pro-

viding a safety feature preventing injury to his hands by inadvertently starting the press before he has removed his hands from the press.

The shifting of the switch 88 to the semi-automatic position energizes the main contactor 86, and as a consequence energizes the solenoid 50. The energization of the contactor coil 108 is accomplished by way of the lines 103 and 95, the forward push-button switch 90, the line 93, the combined switch 88, the lines 102 and 109, the line 107, the combined switch 89, the limit switch 92, the oil temperature limit switch 91, the tonnage control switch 58 and the line 118 to the branch power line 85. The energization is maintained by the closing of the interlock switch blade 110 upon its contacts.

The energization of the solenoid 50 pushes its armature 49 downwardly and raises the control rod 36 so as to shift the valve rod 35 into a position where the pump 27 will deliver pressure fluid to the top of the main cylinder 20 through the line 51. The main plunger 19 and platen 18 move downwardly and engage the workpiece. When the resistance thus built up exceeds the pressure setting of the tonnage control switch 58, the latter opens the circuit in the line 118. This deenergizes the operating coil 108 of the main magnetic contactor 86 and consequently deenergizes the solenoid 50. A spring 119 (Figure 3) at the upper end of the valve rod 35 then forces the control rod 36 downwardly into the position shown in Figure 5, thereby closing the circuit-conditioning switch 43.

In Figure 3 the switches 42 and 43 and cam 39 are shown in the neutral position of the press, where the platen 18 is halted at the upper end of its stroke. In Figure 4 the control rod 36 and cam 39 have been raised from the neutral position of Figure 3 but while the automatic restarting switch 42 has been shifted by the cam 39 no change occurs in the electrical circuit because the circuit-conditioning switch 43 has not yet been engaged and has not prepared the circuit for energization by the automatic restarting switch 42. In other words, the closing of the circuit-conditioning switch 43 is a necessary preliminary to the effective operation of the automatic restarting switch 42.

The deenergization of the solenoid 50 permits the spring 119 to force the control rod 36 downwardly into the Figure 5 position, closing the circuit-conditioning switch 43, as previously as stated. The consequent shifting of the main control valve 31 reverses the flow of fluid by discharging pressure fluid into the push-back cylinders 16 and exhausting fluid from the upper part of the main cylinder 20 by way of the conduit 51. The main plunger 19 and platen 18 then rise, under the urge of the push-back plungers 17, until the platen arm 38 engages the collar 37 and lifts the control rod 36 and valve rod 35 as the platen 18 nears the upper end of its retraction stroke. The lifting of the valve rod 35 shifts the valve 31 into its neutral position, whereby the discharge of the pump 27 is bypassed back to the surge tank 21 and fluid is held in both the main cylinder 20 and push-back cylinders 16. The main platen 18 thus comes to a halt at the upper end of its retraction stroke.

If full automatic operation is desired the operator, as before, depresses the combined switch 88 and the forward switch 90, but returns the combined switch 88 to its full automatic position by a locking device which locks it in that

position. Under these circumstances the platen 18 and main plunger 19 execute a forward stroke and a retraction stroke for their pressure-responsive reversal, as described above under semi-automatic operation. As the platen 18 nears the upper end of its retraction stroke, however, the cam 39 on the control rod 36, which has already depressed the circuit-conditioning switch 43 on the downward stroke of the control rod 36 following the deenergization of the solenoid 50, now depresses the automatic restarting switch 42 as the control rod 36 is lifted by the platen arm 38 engaging the collar 37.

The closing of the circuit-conditioning switch 43 (Figure 6) immediately energizes the auxiliary contactor 87 by way of the line 103, the operating coil 100, the line 104, the switch 43, the lines 106 and 107, the combined switch 89, the limit switches 92, 91 and 58 and the line 118. The consequent closing of the interlock switch blade 98 closes a holding circuit around the circuit-conditioning switch 43 by way of the lines 104 and 105 so as to maintain the energization of the auxiliary contactor 87 when the circuit-conditioning switch 43 is released by the cam 39 on the upward stroke of the press control rod 36.

The closing of the magnetic contactor 87 causes its switch blade 97 to close the gap between the lines 96 and 101. When the cam 39 closes the automatic restarting switch 42 thereafter, the circuit is completed from the branch power line 84, through the lines 103, 95 and 94, the now closed switch 42, the line 96, the switch blade 97, the line 101, the combined switch 88, the lines 102 and 109, the main contactor operating coil 108, the line 107, the combined switch 89, the limit switches 92, 91 and 58 and the line 118 to the branch power line 85. This reenergizes and recloses the main contactor 86 and consequently reenergizes the solenoid 50. The latter again pushes its armature 49 downwardly to raise the control rod 36 and shift the valve 31 to a ram-advancing position. The main plunger 19 then executes another forward stroke, and automatically reverses itself and returns in the manner previously described, continuing to execute an indefinite number of working cycles until halted by the operator or by one of the safety switches.

Thus the provision of the circuit-conditioning switch 43 permits the automatic restarting switch 42 to be effective to reenergize the main contactor 86 and solenoid 50 solely upon the upward stroke of the press control rod 36, and not upon the downward stroke thereof. This feature permits the solenoid 50 to be placed within the housing 13 (Figure 3) along with the other electrical apparatus, and thereby concentrates the electrical apparatus in one location.

Modified construction

The modification shown in Figures 7 to 12 is similar to the form shown in Figures 1 to 6 as regards the press construction generally. The press bed 10 is provided with a movable carrier 120 mounted upon a cushioning plunger 121, reciprocable in a cushioning cylinder 122. The bed is also provided with a hand lever 125 mounted upon a shaft 126, carrying a yoke arm 127 (Figure 11) engaging a collar 128 upon the press control rod 36. The lower end of the press control rod 36 is provided, as before, with a connection 44 pivotally attached to a lever 129 having its outer end pivotally mounted upon the pin 130

in the anchor rod 131, the upper end of which is secured by the screw 132 to the press bed 10.

The inner end of the lever 129 carries a pair of spaced plates 133 having a pivot pin 134 pivotally supporting a latch 135 (Figures 7 and 8), one end of which engages a stop portion 136 upon the lever 129 (Figures 9 and 10). The spaced plates 133 also carry a pivot pin 137, to which is attached the link 138 pivotally connected to the armature 139 of a pull type solenoid 140. The latter is mounted upon the press bed (Figure 7). The cushioning cylinder 122 also serves to support a single automatic restarting switch 142 having a contact portion 141 engageable by the outer end of the latch 135 when the link 138 is pulled upward by the energization of the solenoid 140 (Figure 9). When the solenoid is deenergized, however, and the spring 119 on the upper end of the valve rod 35 forces the press control rod 36 downwardly (Figure 10), the latch 135 tilts and slips past the contact portion 141 of the switch 142 without actuating it. In this manner the automatic restarting switch 142 is actuated only upon the upward stroke of the press control rod 36, but is not actuated upon the downward stroke thereof.

Modified electrical circuit

The modified electrical control circuit (Figure 12) for the modification shown in Figures 7 to 11 is similar to the control circuit shown in Figure 6, except that the auxiliary contactor 87, the circuit-conditioning switch 43 and the associated lines 105, 106, 104 and 103 have been eliminated. The line 96 is thus directly connected to the line 101. The solenoid 140, however, is of the pull type, whereas the solenoid 50 (Figure 6) is of the push type.

Operation

The semi-automatic operation of the modification shown in Figures 7 to 12 is similar to that of the press circuit shown in Figures 1 to 6. In full automatic operation, however, when the combined switch 88 has been shifted into its upper or full automatic position, the automatic restarting switch 142 is closed by the lifting of the press control rod 36 when the platen arm 38 engages the collar 37 as the platen 18 nears the end of its retraction stroke. This is accomplished by the action of the lever 129 and latch 135 (Figure 9). The closing of the automatic restarting switch 142 immediately reenergizes the solenoid 140 to continue the lifting of the press control rod 36, shifting the valve 31 into its forward delivery position and effecting a repeated forward stroke of the press platen 18 immediately after the preceding retraction stroke. When the press platen has arrived at the end of its forward stroke and the pressure switch or tonnage control 58 deenergizes the solenoid 140, the consequent pushing down of the press control rod 36 by the spring 119 does not affect the automatic restarting switch 142 because the latch 135 merely tilts about its pivot (Figure 10) and slips harmlessly past the contact member 141 thereof.

In both of the foregoing forms of press control circuits an open circuit employing a pump 27 and a four-way reversing valve 31 has been illustrated. It will be understood, however, that the press control rod 35 may be connected through appropriate mechanism to the flow-control member of a reversible variable delivery pump so that the pump itself is reversed upon the raising of the control rod 36.

It will be understood that I desire to compre-

hend within my invention such modifications as come within the scope of the claims.

Having thus fully described my invention, what I claim as new and desire to secure by Letters Patent, is:

1. In a hydraulic press control system, the combination with reversible hydraulic motor means having a reciprocable ram and a source of pressure fluid therefor with a flow-control member for reversibly controlling the distribution of pressure fluid to said hydraulic motor means, of electrical means for actuating said flow-control member, a press control element interconnecting said flow-control member and said electrical means and being engageable by said ram, said press control element being adapted to vary the position of said flow-control member, a circuit energization controller connected to control the energization of said electrical means and operable by said control element, and means for rendering said controller effective to influence the energization of said electrical means in only one direction of motion of said control element for automatically starting a new working stroke at the end of the retraction stroke.

2. In a hydraulic press control system, the combination with reversible hydraulic motor means having a reciprocable ram and a source of pressure fluid therefor with a flow-control member for reversibly controlling the distribution of pressure fluid to said hydraulic motor means, of electrical means for actuating said flow-control member, a press control element positively connected with said flow-control member and adapted to be engaged and moved by said ram, said press control element forming a lever arm in a linkage interconnecting said electrical means and said flow-control member, a circuit energization controller connected to control the energization of said electrical means and operable by said control element, and means for activating said circuit energization controller in only one direction of motion of said control element for automatically starting a new working stroke at the end of the retraction stroke.

3. In a hydraulic press control system, the combination with reversible hydraulic motor means having a reciprocable ram and a source of pressure fluid therefor with a flow-control member for reversibly controlling the distribution of pressure fluid to said hydraulic motor means, of electrical means for actuating said flow-control member, a press control element connected to said flow-control member and adapted selectively to move in unison with the latter in one or the other direction, said press control element being engageable by said ram, a circuit energization controller connected to control the energization of said electrical means, and a circuit-conditioning device in circuit with said controller and engageable by said press control element for conditioning said controller for energizing said electrical means in response to the motion of said press control element in only one direction for automatically starting a new working stroke at the end of the retraction stroke.

4. In a hydraulic press control system, the combination with reversible hydraulic motor means having a reciprocable ram and a source of pressure fluid therefor with a flow-control member for reversibly controlling the distribution of pressure fluid to said hydraulic motor means, of electrical means for actuating said flow-control member, a press control element positively connected to said flow-control member

and said electrical means, said press control element being engageable by said ram, a circuit energization controller connected to control the energization of said electrical means, and a circuit-conditioning device in circuit with said controller and engageable by said press control element for conditioning said controller for energizing said electrical means in response to the motion of said press control element in only one direction, for automatically starting a new working stroke at the end of the retraction stroke said circuit controller being ineffective to alter the energization of said electrical means in the opposite direction of motion.

5. In a hydraulic press control system, the combination with reversible hydraulic motor means having a reciprocable ram and a source of pressure fluid therefor with a flow-control member for reversibly controlling the distribution of pressure fluid to said hydraulic motor means, of electrical means for actuating said flow-control member, a press control element connected to said flow-control member so as to be reciprocable therewith and engageable by said ram, a circuit energization controller connected to control the energization of said electrical means and engageable by said control element in both directions of motion thereof, and means for rendering said controller electrically effective in only one direction of motion of said control element, said source of pressure fluid and said flow-control member being disposed near one end of the press and said electrical means near the other end of the press, and said flow-control member and said electrical means being interconnected by said press control element.

6. In a hydraulic press control system, the combination with reversible hydraulic motor means having a reciprocable ram and a source of pressure fluid therefor with a flow-control member for reversibly controlling the distribution of pressure fluid to said hydraulic motor means, of electrical means for actuating said flow-control member, a press control element positively connected on one hand to said flow-control member and on the other hand to said electric means, said press control element being engageable by said ram, a circuit energization controller connected to control the energization of said electrical means and engageable by said control element in both directions of motion thereof, and means for rendering said controller electrically effective in only one direction of motion of said control element, said electrical means comprising a solenoid disposed at the opposite end of the press from said flow-control member.

7. In a hydraulic press control system, the combination with reversible hydraulic motor means having a reciprocable ram and a source of pressure fluid therefor with a flow-control member for reversibly controlling the distribution of pressure fluid to said hydraulic motor means, of electrical means for actuating said flow-control member, a reciprocable press control element positively interconnecting said flow-control member and said electrical means and being engageable by said ram, a circuit energization controller connected to control the energization of said electrical means and engageable by said control element in both directions of motion thereof, and means connected to said press control element for actuating said circuit controller in only one direction of motion of said press control element.

8. In a hydraulic press control system, the

combination with reversible hydraulic motor means having a reciprocable ram and a source of pressure fluid therefor with a flow-control member for reversibly controlling the distribution of pressure fluid to said hydraulic motor means, of electrical means for actuating said flow-control member, a press control element positively connected to said flow-control member so as to be adapted to reciprocate together therewith, said press control element being engageable by said ram and interconnecting said electrical means and said flow-control member, a circuit energization controller connected to control the energization of said electrical means and operable by said control element, and mechanical means connected to said press control element and engageable to actuate said circuit controller in only one direction of motion of said press control element.

9. In a hydraulic press control system, the combination with reversible hydraulic motor means having a reciprocable ram and a source of pressure fluid therefor with a flow-control member for reversibly controlling the distribution of pressure fluid to said hydraulic motor means, of electrical means including a movable element for actuating said flow-control member, a press control element interconnecting said flow-control member and said movable element and being engageable by said ram, a circuit energization controller connected to control the energization of said electrical means and operable by said control element, and a latch mechanism connected to said press control element and arranged to actuate said circuit controller in only one direction of motion of said press control element.

10. In a hydraulic press control system, the combination with reversible hydraulic motor means having a reciprocable ram and a source of pressure fluid therefor with a flow-control member for reversibly controlling the distribution of pressure fluid to said hydraulic motor means, of electrical means including a movable element for actuating said flow-control member, a press control element movably connected to said flow-control member and interconnecting said flow-control member and said movable element, said press control element being engageable by said ram, a circuit energization controller connected to control the energization of said electrical means and operable by said control element, and a latch mechanism connected to said press control element and including a pivoting member tiltable about its pivot to slip by said circuit controller in one direction of motion of said press control element without operating said circuit controller and to engage and operate said circuit controller in the opposite direction of its motion.

11. In a hydraulic press in combination, hydraulic motor means, a fluid source for supplying pressure fluid to said motor means to actuate the same, flow controlling means for reversibly controlling the distribution of pressure fluid to said motor means, a control member, relay means adapted when energized to move said control member, said control member being positively connected with a movable element of said relay means and forming a link in a lever system interconnecting said movable element and said controlling means, switch means controlling the energization of said relay means and engageable by said control member during the working stroke and the retraction stroke of said motor means and means for preventing energization of said relay means by said switch means before said

motor means has reached the end of its retraction stroke.

12. In combination in a hydraulic press, hydraulic motor means, a fluid source for supplying pressure fluid to said motor means to actuate the same, flow controlling means associated with the said fluid source and reversibly controlling the distribution of pressure fluid to said motor means, electric relay means to actuate said controlling means, a reciprocable control member

positively interconnecting said relay means and said flow controlling means and having cam means associated therewith, switch means adapted to control the energization of said relay means and being engageable by said cam means at each stroke of said control member, and means for preventing energization of said relay means by said switch means before said motor means has reached the end of its retraction stroke.

PAUL E. FLOWERS.
